(57) **CLAIM**

The ornamental design for a wireless microphone, as shown
and described.

DESCRIPTION

The article to which the design is applied is a wireless
microphone comprising a microphone and a wireless trans-
mitter which is detachable from the microphone.

The present design is characterized by “a sense of duty” in
appearance of the microphone with the wireless transmitter.
No wire for transmitting radio waves is drawn out from the
transmitter.

FIG. 1 is a perspective view of a wireless microphone
showing my new design;

FIG. 2 is a top plan view thereof;

FIG. 3 is a rear elevational view thereof;

FIG. 4 is a left side elevational view thereof;

FIG. 5 is a front elevational view thereof;

FIG. 6 is a right side elevational view thereof; and,

FIG. 7 is a bottom plan view thereof.
